UNITED STATES PATENT OFFICE

167,117

COMBINED BANK AND PICTURE FRAME

Berle B. Salmon, Montreal, Quebec, Canada, assignor to Edith Jacques Clark, Westmont, Quebec, Canada

Application September 19, 1950, Serial No. 12,258

Term of patent 14 years

(Cl. D34—11)

To all whom it may concern:

Be it known that I, Berle B. Salmon, a citizen of Canada and a resident of Montreal, Province of Quebec, Dominion of Canada, have invented a new, original, and ornamental Design for a Combined Bank and Picture Frame, of which the following is a specification, reference being had to the accompanying drawing, forming part thereof.

The single drawing figure is a perspective view of a combined bank and picture frame. The dotted lines shown in the drawing are for illustrative purposes only and the drawing is shaded to indicate transparency.

I claim:

The ornamental design for a combined bank and picture frame, as shown and described.

BERLE B. SALMON.
